UNITED STATES PATENT OFFICE.

BERNE NADALL, OF KINGSTON-UPON-THAMES, ENGLAND, ASSIGNOR TO
THE LINOTYPE COMPANY, LIMITED, OF LONDON, ENGLAND.

DESIGN FOR A FONT OF TYPE.

SPECIFICATION forming part of Design No. 35,711, dated February 11, 1902.

Application filed May 17, 1901. Serial No. 60,774. Term of patent 14 years.

To all whom it may concern:

Be it known that I, BERNE NADALL, a citizen of the United States of America, residing at Kingston-upon-Thames, in the county of 5 Surrey, England, have invented and produced a new and original Design for a Font of Type, of which the following is a specification.

The present new and original design for a font of printing-type is illustrated in the accompanying drawings, the upper-case letters, characters, numerals, and punctuation-marks being shown on one sheet and the lower-case letters on a second sheet.

The first striking characteristic of the present design is that all of the lines forming the letters, characters, &c., are of the same density or appearance—that is, impressions from type embodying the present design do not present combinations of light and heavy lines, but all of the lines are equally heavy. Most of the letters and characters also present other distinguishing features, some of which will be now enumerated.

In many letters in the font there is a concave fillet at the junction of a horizontal with a vertical line.

The horizontal line of the letter A is arranged relatively near the lower ends of the two inclined lines, and the upper end of the 30 right-hand inclined line is curved and projects slightly beyond the outer face of the left-hand line of the letter.

The upper member of the letter B is considerably smaller, both as regards height and 35 width, than the lower member, and the line separating said members is inclined upwardly toward the perpendicular forming the left-hand line of the letter. This inclined division-line connects with said perpendicular for only a portion of its left-hand end.

In the letter C the ends of the curved line are comparatively widely separated and the upper end is expanded or is slightly wider than the body of said letter adjacent said end. 45 The lower end of said curve is tapered, the face of such end being inclined to the perpendicular.

The letter D is formed by a perpendicular, two horizontals, and a curved line uniting the 50 right-hand ends of the horizontals.

Several of the letters in which horizontal lines are employed are marked by having the

free ends of such lines expanded somewhat, or, in other words, by forming said horizontals with one edge straight and the other slightly curved. This is particularly noticeable in the upper and lower horizontal lines of the letters E and Z, the upper horizontals of the letters F and T, and the lower horizontal of the letter L. The upper and lower curves of 60 the letter S are also expanded slightly at their outer ends. The letters E and F are also distinguished in that the middle horizontal line of the former and the lower horizontal of the latter are curved or bent down- 65 wardly slightly at their outer ends.

The face of the upper end of the curve of the letter G is perpendicular, while the end of the perpendicular line in which the lower end of said curve terminates is inclined to 70 the horizontal.

The horizontal line of the letter H is situated somewhat above the middle.

The letter J is formed by a single perpendicular having a slight curve at one end, the 75 face of the end of said curve being inclined. This letter is slightly longer than the others.

In the letter K the upper inclined line is connected with the left perpendicular relatively near the lower end of the letter, and 80 the other shorter inclined line is connected to the first at a point about midway of its length and at some distance from the perpendicular.

The right-hand inclined line of the letter 85 M extends somewhat beyond the left-hand inclined line, and its projecting portion is tapered and curved or bent slightly toward the left perpendicular. The lower terminal of the right-hand perpendicular of the letter N. 90 is similarly formed with relation to the inclined line of said letter.

The letter O is formed by two curves meeting in relatively pointed upper and lower ends.

The body of the letter P is formed, like the 95 letter D, above described, by a perpendicular, two horizontals, and a curve uniting the right-hand ends of the horizontals.

The letter Q has the same body formation as the letter O, and the tail or projection thereon is wholly below said figure and curved but slightly to the right. 100

The upper portion of the letter R is similarly formed to the upper portion of the let-

ter B, the lower side of said body contacting with the left-hand perpendicular a portion of its length only.

5 The lower end of the left-hand line of the letter V is curved slightly and extends across the lower end of the right-hand end of said letter.

10 In the letter W the left-hand line and the intermediate line parallel thereto are similar in form to the corresponding line in the letter V. The longer intermediate line, which is parallel to the right-hand line of the letter, extends above the other intermediate line and at its free end is deflected slightly toward the left.

15 The letters A and E used in the diphthongs illustrated present the characteristics hereinbefore pointed out.

20 The pounds-sign is formed by an ogee curve and two horizontal lines, the lower one extending to the right from the lower end of said curve and the upper and thinner one crossing said curve about midway of its height.

25 The dollars-mark is formed by a combination curve crossed by a single perpendicular.

The curved and horizontal lines used in forming the several numerals are generally similar in form to those employed in forming the letters before described—that is, said lines are relatively wider or expanded at their free ends than where they are united to others. This same feature of having slightly-expanded terminals also distinguishes many of the letters of the lower case, being particularly noticeable in the letters a, b, e, f, g, r, s, and z. The lower-case e is also noticeable in that the line connecting the upper end of the curve with the body thereof is not horizontal, but is inclined downwardly from the horizontal. 35

Having thus described my invention, what I claim, and desire to secure by Letters Patent, is—

The design for a font of printing-type, substantially as shown and described.

40 In testimony whereof I affix my signature in presence of two witnesses.

BERNE NADALL.
